UNITED STATES PATENT OFFICE.

WILLIAM T. HATMAKER AND EARL E. EICKMEYER, OF DAYTON, OHIO, ASSIGNORS TO THE NATIONAL RECORDING PUMP COMPANY, OF DAYTON, OHIO, A CORPORATION OF OHIO.

LIQUID-DISPENSING APPARATUS.

Application filed June 21, 1924. Serial No. 721,485.

This invention relates to a liquid dispensing apparatus and more particularly to a device for controlling the connection between the pump and the discharge line.

5 In liquid measuring pumps and more especially in measuring pumps of the piston type there is a tendency on the part of the column of liquid to continue its movement after the piston, or other discharge device, 10 has completed its operative movement or delivery stroke, this being due to the inertia of the column of liquid. During the delivery stroke of the piston of a piston pump the column of liquid moves at a considerable 15 velocity and when the piston is suddenly stopped at the end of its delivery stroke the column of liquid will continue its movement until the inertia is overcome by gravity and friction and consequently there is often a 20 material over-delivery of liquid.

The main object of the present invention is to provide means for interrupting the flow of liquid from the pump casing to the discharge line immediately upon the completion 25 of the delivery of a predetermined quantity of such liquid.

To this end it is a further object of this invention to provide means, the operation of which is controlled by the piston, to cause 30 the connection between the pump cylinder and the discharge line to be interrupted at the end of the delivery stroke of the piston.

A further object of the invention is to provide such a device which will be simple 35 in its construction, positive in its operation and which will not in any way interfere with the normal operation of the dispensing apparatus.

Other objects of the invention will appear 40 as the device is described in detail.

In the accompanying drawings Fig. 1 is a side elevation of a dispensing apparatus, with the casing in section, showing our invention applied thereto; Fig. 2 is a transverse section taken on the line 2—2 of Fig. 45 1; Fig. 3 is a vertical section taken on the line 3—3 of Fig. 2; Fig. 4 is a vertical section taken on the line 4—4 of Fig. 3; Fig. 5 is a detail view of the rotatable valve member; and Fig. 6 is a detail view of the connecting member.

In these drawings we have illustrated one embodiment of our invention and have shown the same as applied to a double 55 cylinder gasoline dispensing pump of a well

known type and, further, have shown the controlling device in the form of a rotatable valve but it will be understood that this particular embodiment has been chosen for the purpose of illustration only and that 60 the controlling mechanism may take various forms and that it may be applied to pumps of various kinds.

The particular pump here shown comprises two cylinders 1 mounted upon a base 65 2 and having mounted therein the usual pistons, one of which is shown at 3 in Fig. 3. These pistons are connected with and actuated by piston rods 4 to which movement may be imparted in any suitable manner. 70 Means are provided for connecting both cylinders with a discharge line 5. In the present instance, this discharge line is connected with the cylinders through a manually operated valve 6 which controls a bypass but inasmuch as this by-pass forms no part of the present invention it is not shown in detail or described herein and the by-pass valve 6 may be disregarded in the consideration 75 of the controlling device as it is normally in a position to directly connect the discharge line with the cylinders. Between each cylinder and the discharge line is a suitable cut-off to control the flow of liquid from the cylinder to the discharge line. In 80 the present construction, we have utilized a single cut-off to control the connection between both cylinders and the discharge line. This cut-off may be of any suitable character 85 and may be controlled in any suitable manner which will cause the connection between either cylinder and the discharge line to be interrupted immediately upon the completion 90 of the delivery stroke of the piston in that cylinder. In the present apparatus the 95 upper ends of the cylinders 1 are closed by a single casting or cylinder head 7 which is provided with a cavity or chamber 8 in line with the respective cylinders, the two chambers in the cylinder head or casting being 100 separated by a partition 9. The connection between the discharge line and the cylinders is, in the present instance, formed through this partition and, in the device here shown, we have utilized a rotary valve as the controlling element. Therefore, we have formed 105 in the partition 9 a cylindrical valve chamber 10 having ports 11 connecting the same with the respective cylinders 1 and having a port 12 connecting the same with the dis- 110

charge line, through the by-pass valve 6. Rotatably mounted in the valve chamber is a hollow valve member 13 which is provided with a series of ports 14 so arranged that 5 the rotation of the valve will cause the connection between the discharge line and one or the other of the cylinders to be interrupted. In the present construction the arrangement of the ports 14 is such that when 10 one cylinder is disconnected from the discharge line the other cylinder will be connected therewith.

The cut-off or rotatable valve may be actuated in any suitable manner to automatically interrupt the connection between 15 one of the cylinders and the discharge line when the piston in that cylinder has completed its delivery stroke, thereby interrupting the flow of liquid and preventing over-delivery. In the present form of the apparatus the actuating devices are mounted 20 in the cylinder head at the upper ends of the respective cylinders and are controlled by the respective pistons. Preferably each 25 actuating device is in the form of an arm 15 pivotally supported within the cylinder head, operatively connected with the valve and having a part arranged to be engaged by the piston or a part connected therewith, 30 to actuate the arm and the valve. In the particular form of actuating arm here shown, the outer or pivoted end of the arm is bifurcated and the parts 16 of the bifurcated portion of the arm extend on opposite sides 35 of the piston rod 4 and are provided with openings to receive trunnions 17 which are mounted in suitable bearings 18 arranged within the cylinder head. If desired, the bearings 18 may be formed in a bracket 40 or bearing frame 19 which is removably mounted in the cylinder head by means of screws 20 extending through the same into lugs 21 depending from the outer wall of 45 the cylinder head. The purpose of this arrangement is to enable the bearings for the trunnions 17 to be formed without the necessity of boring through the side walls of the cylinder head. The actuating arm 15 is provided with a part arranged to be 50 engaged by the piston 3, or the part carried thereby, just before that piston completes its delivery stroke so that the valve will be closed at the time the piston completes its delivery stroke. That part of the 55 arm which is engaged by the piston is spaced some distance from that end of the arm which is connected with the valve and consequently a very slight movement of the piston will effect an operative movement of the valve member. In the present construction the actuating arm is provided with two 60 depending lugs 22 between which is rotatably supported a roller 23 which is arranged to be engaged by the piston, or a part connected therewith, and serves to minimize

the frictional contact between the arm and the piston. As here shown, the part which engages the roller and imparts movement to the actuating arm is in the form of a cam which may be connected either with 70 the piston or with the piston rod and, in the present instance, is connected with both parts and forms a part of the piston. In the form illustrated, the cam is shown at 75 31 in the form of a projection forming a part of the piston and extending upwardly from the piston head and having a tapered upper portion with which the piston rod is connected and which provides a cam surface for the projection. That portion of the projection between the cam surface and the piston head is cylindrical and of sufficient length to permit the amount of movement which will be imparted to the piston by each stroke of the piston rod to be regulated without varying the movement of the valve.

The actuating arm may be connected with the valve member in any suitable manner but, in the present arrangement, the valve member 13 terminates some distance from the rear end of the chamber 10. Rotatably mounted in the rear portion of the chamber 10 is a connecting member or cylindrical block 24 which is spaced from the rear closed end of the valve member 13 and is connected separably but non-rotatably therewith. In the present instance, this connection is formed by an axial pin or trunnion 25, extending into both the connecting member and valve member, and by a dowel pin 26 also extending into both of said members, thus holding the same against relative rotation. That face of the connecting member 24 adjacent to the valve member is provided on opposite sides of its center with recesses 27 into which extend projections or rollers 28 extending laterally from the respective actuating arms 15, the arrangement of the recesses being such that the projections 28 can have a slight radial movement relative to the connecting member as the latter is rotated. The arms 15 extend through slots 29 in the adjacent sides of the partition or walls of the valve chamber 10. The outer or front end of the valve chamber is closed by a cap 30 which is screw threaded into that chamber and serves both to close the chamber and to hold the valve member against axial displacement. By removing the cap 30 the valve member may be withdrawn from the valve chamber without displacing the actuating arms 15, which will maintain their normal connections with the connecting member 24. When the valve member is reinserted in the chamber the axial pin 25 will enter the corresponding opening and it is only necessary to so position the valve that the dowel pin will enter its opening, thus enabling the valve to be 130

very easily and very quickly removed from and reinserted in the valve chamber.

The operation of the device will be readily understood from the foregoing description and it will be apparent that we have provided a dispensing apparatus of this character in which an over-delivery of liquid, due to inertia of the column of the liquid, is positively prevented; that the apparatus for accomplishing this result is very simple in its construction, is positively operated by the piston itself and does not in any way interfere with the normal operation of the dispensing apparatus.

While we have shown and described one embodiment of our invention we wish it to be understood that we do not desire to be limited to the details thereof as various modifications may appear to a person skilled in the art.

Having now fully described our invention, what we claim as new and desire to secure by Letters Patent, is:

1. In a dispensing apparatus, a cylinder, a piston mounted in said cylinder, means for actuating said piston, a discharge line connected with said cylinder, a cut-off to control said connection, and means supported independently of said cut-off for automatically closing said cut-off when a predetermined quantity of liquid has been discharged from said cylinder.

2. In a dispensing apparatus, a cylinder, a piston mounted in said cylinder, means for actuating said piston, a discharge line connected with said cylinder, a cut-off to control said connection, and means supported independently of said cut-off for automatically closing said cut-off at the end of the delivery stroke of said piston.

3. In a dispensing apparatus, a cylinder, a piston mounted in said cylinder, means for actuating said piston, a discharge line connected with said cylinder, a cut-off to control said connection, and a device supported independently of said cut-off and controlled by said piston to actuate said cut-off.

4. In a dispensing apparatus, a cylinder, a piston mounted in said cylinder, means for actuating said piston, a discharge line connected with said cylinder, a valve interposed between said discharge line and said cylinder, and an actuating device for said valve supported independently thereof and arranged to be operated by said piston.

5. In a dispensing apparatus, a cylinder, a piston mounted in said cylinder, means for actuating said piston, a discharge line connected with said cylinder, a valve interposed between said cylinder and said discharge line, an actuating device for said valve mounted independently of said valve at one end of said cylinder and having a part adapted to be engaged by said piston to cause said valve to be actuated.

6. In a dispensing apparatus, a cylinder, a piston mounted in said cylinder, means for actuating said piston, a discharge line connected with said cylinder, a valve interposed between said discharge line and said cylinder, an arm pivotally mounted on a fixed support at one end of said cylinder, operatively connected with said valve and having a part extending into the path of said piston.

7. In a dispensing apparatus, a cylinder, a hollow cylinder head, a piston mounted in said cylinder, means for actuating said piston, a discharge line connected with said cylinder, a valve interposed between said discharge line and said cylinder, and an actuating device for said valve mounted in said hollow cylinder head independently of said valve and controlled by said piston.

8. In a dispensing apparatus, a cylinder, a hollow cylinder head, a piston mounted in said cylinder, means for actuating said piston, a discharge line connected with said cylinder, a valve interposed between said discharge line and said cylinder, and an actuating device pivotally mounted within said cylinder head, having a part operatively connected with said valve and having a part arranged in the path of said piston.

9. In a dispensing apparatus, a cylinder, a hollow cylinder head, a piston mounted in said cylinder, means for actuating said piston, a discharge line connected with said cylinder, a valve interposed between said discharge line and said cylinder, an actuating device having one end operatively connected with said valve, having its other end pivotally mounted within the hollow cylinder head and having a part arranged between the ends thereof and adapted to be engaged by said piston.

10. In a dispensing apparatus, a cylinder, a hollow cylinder head, a piston mounted in said cylinder, means for actuating said piston, a discharge line connected with said cylinder, a rotatable valve interposed between said cylinder and said discharge line, an actuating device mounted in said hollow cylinder head, operatively connected with said rotatable valve and having a part arranged to be actuated by said piston.

11. In a dispensing apparatus, a cylinder head having a valve chamber, a discharge chamber connected with said valve chamber, a valve rotatably mounted in said valve chamber, a piston mounted in said cylinder, and means for actuating said piston, and an arm pivotally mounted within said cylinder head, operatively connected with said rotatable valve and having a part arranged to be engaged by said piston.

12. In a dispensing apparatus, a pair of cylinders, an end member connected with both cylinders and having chambers in line with the respective cylinders, a partition separating said chambers and having a valve

- 4
- chamber formed therein and communicating with both of said cylinders, a discharge line communicating with said valve chamber, a valve rotatably mounted in said valve chamber, actuating devices mounted in the respective chambers in said casing independently of said valve and each operatively connected with said valve, pistons mounted in the respective cylinders and adapted to actuate the respective valve actuating devices, and means for actuating said pistons.
13. In a dispensing apparatus, a cylinder, a cylinder head having an elongated valve chamber communicating with said cylinder, a discharge line communicating with said valve chamber, a piston mounted in said cylinder, means for actuating said piston, a valve rotatably mounted in said valve chamber, a connecting member rotatably mounted in said chamber and having operative connection with said valve, and an actuating device operatively connected with said connecting member and having a part arranged to be engaged by said piston.
14. In a dispensing apparatus, a cylinder, a cylinder head having an elongated valve chamber communicating with said cylinder, a discharge line communicating with said valve chamber, a piston mounted in said cylinder, means for actuating said piston, a valve rotatably mounted in said valve chamber, a connecting member rotatably mounted in said valve chamber in axial alinement with said valve, means for detachably connecting said connecting member with said valve, said connecting member being spaced from the adjacent end of said valve and having a recess in that face thereof adjacent to said valve, and an actuating device pivotally mounted in said cylinder head, having a part adapted to enter the recess in said connecting member and having a part arranged to be engaged by said piston.
15. In a dispensing apparatus, a cylinder, a hollow cylinder head, a piston mounted in said cylinder, means for actuating said piston, a discharge line connected with said cylinder, a valve to control the connection between said discharge line and said cylinder, a bearing bracket arranged within said cylinder head and secured to the end wall thereof and having alined bearings arranged near the opposite sides of said cylinder head, an actuating arm having one end bifurcated to extend on opposite sides of said piston rod and provided with trunnions mounted in
- said bearings, means for operatively connecting the other end of said arm with said valve, said arm also having a part arranged in the path of said piston.
16. In a dispensing apparatus, a cylinder, a piston mounted in said cylinder, means for actuating said piston, a discharge line connected with said cylinder, a cut-off to control said connection, and a device supported independently of said cut-off to actuate said cut-off, said piston having a part arranged to impart movement to said actuating device.
17. In a dispensing apparatus, a cylinder, a piston mounted in said cylinder, means for actuating said piston, a discharge line connected with said cylinder, a cut-off to control said connection, a device to actuate said cut-off, and a cam connected with said piston, having a part to impart operative movement to said actuating device and another part to retain said actuating device in the position to which it has been moved during the further movement of said piston.
18. In a dispensing apparatus, a cylinder, a piston mounted in said cylinder, means for actuating said piston, a discharge line connected with said cylinder, a cut-off to control said connection, a device to actuate said cut-off, and a part carried by said piston to impart movement to said actuating device, said part having a cam shaped portion and also having a straight portion between said cam shaped portion and said piston.
19. In a dispensing apparatus, a cylinder, a piston mounted in said cylinder, means for actuating said piston, a discharge line connected with said cylinder, a cut-off to control said connection, a device to actuate said cut-off, a cylindrical projection carried by said piston and having a tapered end portion connected with said piston rod and arranged to engage said actuating device.
20. In a dispensing apparatus, a cylinder, a piston mounted in said cylinder, a piston rod connected with said piston, a cam carried by one of said parts, a discharge line connected with said cylinder, a cut-off to control the last mentioned connection, and an actuating device for said cut-off having a part arranged to be engaged by said cam.
- In testimony whereof, we affix our signatures hereto.
- WILLIAM T. HATMAKER.
EARL E. EICKMEYER.
